UNITED STATES PATENT OFFICE.

WILLIAM ENGBERG, OF ST. JOSEPH, MICHIGAN.

VALVE-GEAR.

SPECIFICATION forming part of Letters Patent No. 581,577, dated April 27, 1897.

Application filed February 10, 1897. Serial No. 622,783. (No model.)

To all whom it may concern:

Be it known that I, WILLIAM ENGBERG, of St. Joseph, in the county of Berrien and State of Michigan, have invented a new and 5 Improved Valve-Gear, of which the following is a full, clear, and exact description.

The invention relates to valve-gears such as shown and described in the Letters Patent of the United States No. 533,283, granted to 10 me on January 29, 1895.

The object of the present invention is to provide a new and improved valve-gear more especially designed for use in water-supply pipes connecting a pumping-station with a 15 distant stand-pipe, the said gear being very simple and durable in construction, not liable to get out of order, and arranged to enable the engineer in charge of the pumping-station to open or close the supply-pipe to allow the 20 water to pass to the stand-pipe or to cut it off therefrom.

The invention consists principally of a cylinder containing a piston for opening or closing the valve in the supply-pipe, a valve connected with the liquid-supply and with the 25 ends of the said cylinder to move the piston therein up or down by the pressure of the liquid passing from the valve to the said cylinder, and a device electrically controlled 30 and connected with the said valve to open the same to either end of the cylinder, the said device comprising an electric circuit containing two relays and a magnet for each relay, the magnets having each an armature-lever, two slidable bars adapted to be engaged and locked by the respective armature-levers and controlling the position of the 35 valve, and means controlled by the said piston for making ground connection for either 40 relay and adapted to engage and move the said bars in opposite directions.

The invention also consists of certain parts and details and combinations of the same, as will be fully described hereinafter and then 45 pointed out in the claims.

Reference is to be had to the accompanying drawings, forming a part of this specification, in which similar characters of reference indicate corresponding parts in all the figures.

50 Figure 1 is an end elevation of the improvement as applied and with parts in section.

Fig. 2 is a face view of the improvement with the box in section. Fig. 3 is a rear face view of the box with parts broken out. Fig. 4 is a plan view of the improvement, and Fig. 5 55 is a diagrammatic view showing the electric connections.

The supply-pipe A is connected in the usual manner with a stand-pipe located a suitable distance from the pumping-station, and in 60 the said supply-pipe, near the stand-pipe, is arranged a gate-valve B, having its valve-stem C connected with one end of a piston D', fitted to slide in a cylinder D, supported from the casing of the valve B, as plainly 65 shown in Fig. 1. The piston-rod D² of the piston D' is provided on its outer end with an arm E, made in two sections E' and E², held 70 adjustably one on the other to lengthen and shorten the arm, the said sections being adapted to be fastened together by a suitable set-screw E³. The section E' is secured by a set-screw E⁴ to the said piston-rod D², and the outer end of the other section E² is secured by the said screw E⁵ to a rod F, fitted 75 to slide in suitable bearings in a box G, supported by suitable brackets from the cylinder D.

On the rod F, within the box G, are held adjustably the arms F' and F², of which the arm 80 F' is adapted to engage an arm H', secured on a bar H, fitted to slide in suitable bearings within the box G. The other arm F² is adapted to engage the free end of a lever I', fulcrumed in the box G and pivotally connected 85 with a second bar I, likewise fitted to slide in suitable bearings in the box G.

When the rod F moves upwardly, the arm F' disengages the free end of the lever I', and the other arm F² finally engages the arm H' 90 to lift the bar H. When the rod F moves downwardly, the arm F' leaves the arm H' to free the bar H, and the other arm F² finally engages the free end of the lever I', so as to impart a swinging motion thereto to move the 95 bar I in an upward direction. Both the bars H and I are provided with weights or pressed on by springs, so that when the arms F' and F² relieve the arms H' and I', respectively, the said weights or springs move the bars into 100 a lowermost position, provided the same are unlocked, as hereinafter more fully described.

The lower ends of the bars H and I press loosely on the free ends of a lever J, secured at its middle on the stem K' of the valve K, similar in construction to the valve G shown 5 and described in detail in the patent above referred to. The valve K is provided with a pipe K², connected with a liquid-supply, preferably with the supply-pipe A, as shown, and from the valve leads a discharge-pipe K³, 10 through which water may escape from either end of the cylinder D, it being understood that the valve K is connected by pipes K⁴ and K⁵ with the upper and lower ends of the said cylinder, so that when the valve is in the 15 proper position water can, under pressure, flow from the supply-pipe A to either end of the cylinder to impart motion to the piston D' in either an upward or a downward direction, according to which pipe, K⁴ or K⁵, is connected 20 by the valve K with the pipe K². The supply-pipe K⁴ or K⁵ is then connected with the pipe K³ to allow the opposite end of the cylinder to drain off its water by way of the valve K and pipe K³.

25 The bars H and I are adapted to be locked in an uppermost position by armature-levers L² and L³, respectively, adapted to engage notches H² and I² in the bars H and I, respectively. The armature-levers L² and L³ being 30 long to the electromagnets L and L', connected with the relays N and N', respectively, and electrically connected with each other by the wire N², and by wires N³ and N⁴ with contact-plates O and O', respectively, held insulated in the box G. The contact-plates O and O' are adapted to be engaged by a spring 35 contact-plate F³, secured on the rod F above the uppermost arm F', as plainly shown in Figs. 2 and 5.

40 The electromagnets L and L' and their relays N and N' are connected with a local battery P, and the wire N², connecting the relays with each other, runs to the pumping-station and contains a switch N⁵, connected by the 45 wire Q' with a battery Q, having its other wire Q² connected with the ground. The rod F has a ground connection either by a direct wire, as indicated in Fig. 5, or by means of the arm E, the piston D', cylinder D, and pipe 50 A, usually held underground. Midway between the contact-plates O and O' is arranged a third insulated contact-plate R, connected by a wire R' with an alarm S, arranged in the pumping-station, connected by a wire S' with 55 the battery-wire Q'.

The operation is as follows: When the piston D' is in a lowermost position, as illustrated in Fig. 1, the gate-valve B is closed and water is shut off from the stand-pipe. Now when 60 the engineer in charge of the distant pumping-station desires to open the gate-valve B he closes the switch N⁵ a short time, so that an electric circuit is established by way of wire N², relay N, wire N³, contact-plates O and F³, and the rod F, connected with the ground. As the current also passes through

the electromagnet L, the latter becomes energized, and consequently the armature-lever L² is attracted and moved out of engagement with the bar H, so that the latter can slide 70 downward by the weight or spring, and in doing so turns the lever J, and consequently changes the position of the valve K, so that the pipe K² is connected with the pipe K⁵ and the pipe K⁴ is connected with the pipe K³. 75 Water now flows into the lower end of the cylinder D to push the piston D' in an upward direction to open the gate-valve B and to allow the water to flow from the supply-pipe A into the stand-pipe. When the rod F moves 80 upward with the upward movement of the piston D', the contact-plate F³ finally moves out of engagement with the contact-plate O, so that the circuit is broken, and the said contact-plate finally moves for a short time 85 in engagement with the contact-plate R, so as to complete the circuit for the alarm S, whereby the latter is sounded, and thus notice is given to the engineer in charge that the gate-valve B is opening. When the piston 90 D' finally arrives at an uppermost position, the contact-plate F³ is in engagement with the contact-plate O', and the piston is held in this position by the pressure of the water from the supply-pipe A. During the 95 upward movement of the rod F the arm F' moves in engagement with the arm H' to lift the bar H back into an uppermost position, so that the armature-lever L² can engage the 100 said bar and lock it in an uppermost position. When the engineer again desires to close the gate-valve B, he moves the switch N⁵ for a short time into a closed position, so that it again closes the circuit by way of wire N², relay N', wire N⁴, contact-plates O' and F³, and rod F. 105 The electric current now energizes the electromagnet L', so that the armature L³ thereof is attracted and moved out of engagement with the bar I. As the lower end of the latter now rests on the lever J, it is evident that 110 a downward movement of the said bar, caused by its spring or weight, turns the said lever to shift the position of the valve K and to cause the water to flow into the upper end of the cylinder to push the piston D' downward to close 115 the valve B. When the piston moves downward, the rod F is carried in the same direction and the contact between the plates F³ and O' is broken, and contact is made shortly thereafter by the plate F³ with the plate R to again 120 sound the alarm S, so as to notify the engineer in charge of the pumping-station that the valve is closing. The switch N⁵ is then thrown by the engineer into an open position. The rod F in its downward movement moves 125 in engagement with the free end of the lever I', so as to impart a swinging motion thereto to lift the bar I back to its former position, and as the electromagnets L' are now deenergized the armature-lever L³ again engages 130 and locks the bar I in an uppermost position. When the piston E' arrives in this lowermost

position, the rod F, by its plate F³, again makes contact with the plate O, and the piston is held in a downwardmost position by the pressure of the water until the above-described 5 operation is repeated; that is, when the engineer desires to again open the gate-valve, as before described.

It will be seen that by the arrangement described an alarm will be sounded at the pumping-station in case the valve B is opened or closed accidentally. In order to keep the box free from moisture, I prefer to line the same with zinc or the like.

Having thus fully described my invention, 15 I claim as new and desire to secure by Letters Patent—

1. A valve-gear comprising a cylinder and piston for opening and closing the valve in a supply-pipe, a valve connected with a liquid- 20 supply and also connected with the ends of the said cylinder, to move the piston thereon up or down by the pressure of the liquid passing from the valve to the cylinder, and a device electrically controlled and connected 25 with the said valve to open the same to either end of the cylinder, the said device comprising an electric circuit containing two relays, a magnet for each relay, and provided with an armature-lever, slidable bars adapted to 30 be engaged and locked by the respective armatures, the said bars controlling the position of the valve, and means controlled by the said piston, for making ground connection with either relay and adapted to engage 35 and move the said bars back to a normal position, substantially as shown and described.

2. A valve-gear provided with a controlling device for the valve and comprising an electric circuit containing two relays, an electric mag- 40 net for each relay and provided with an armature-lever, two slidable bars adapted to be engaged and locked by the corresponding armature-levers the said bars controlling the position of the valve, and means for making al- 45 ternate ground connections for the said relays, substantially as shown and described.

3. A valve-gear provided with a controlling device for the valve and comprising an electric circuit containing two relays, an electromag- 50 net for each relay and provided with an armature-lever, a switch in the said circuit, two slidable bars adapted to be engaged and locked by the corresponding armature-levers, the said bars controlling the position of the valve, 55 and means for making alternate ground connections for the said relays and arranged for

connection with the said bars to return the same to their normal locked position, substantially as shown and described.

4. A valve-gear provided with a controlling 60 device for the valve and comprising an electric circuit containing two relays, an electromagnet for each relay and provided with an armature-lever, a switch in the said circuit, two slidable bars adapted to be engaged and locked 65 by the corresponding armature-levers, the said bars controlling the position of the valve, means for making alternate ground connections for the said relays and arranged for connection with the said bars to return the same 70 to their normal locked position, and a second circuit controlling an alarm and adapted to be opened and closed by the said means, substantially as shown and described.

5. A valve-gear provided with a controlling 75 device for the valve and comprising an electric circuit containing two relays, an electromagnet for each relay and provided with an armature-lever, a switch for opening and closing the said circuit, movable bars adapted to be 80 locked in position by the corresponding armature-levers and controlling the position of the valve, and a movable rod having contact- 85 plates adapted to alternately engage the contact-plates for the said relays, to connect the same alternately with the ground, the said rod being also provided with arms for engagement with the said bars to return the same to a locking position, substantially as shown and described. 90

6. A valve-gear provided with a controlling device for the valve and comprising an electric circuit containing two relays, an electromagnet for each relay and provided with an armature-lever, a switch for opening and closing 95 the said circuit, movable bars adapted to be locked in position by the corresponding levers and controlling the position of the valve, a movable rod having contact-plates adapted to alternately engage the contact-plates for 100 the said relays, to connect the same alternately with the ground, the said rod being also provided with arms for engagement with the said bars to return the same to a locking position, and a second circuit having an alarm 105 and provided with a contact-plate adapted to be engaged by a contact-plate of the said rod, substantially as shown and described.
